UNITED STATES PATENT OFFICE.

AMON T. NOE, OF PARNASSUS, PENNSYLVANIA, ASSIGNOR TO ELECTRIC RENOVATOR MANUFACTURING COMPANY, A CORPORATION OF PENNSYLVANIA.

DUST-COLLECTOR.

No. 918,895.

Specification of Letters Patent. Patented April 20, 1909.

Application filed September 21, 1907. Serial No. 393,936.

To all whom it may concern:

Be it known that I, AMON T. NOE, a citizen of the United States, residing at Parnassus, in the county of Westmoreland and State of Pennsylvania, have invented certain new and useful Improvements in Dust-Collectors, of which the following is a specification.

My invention relates to dust collectors, and more particularly to a device of this character designed for use in connection with pneumatic sweeping or renovating apparatus, such as is commonly employed in house-cleaning.

The primary object of my invention is to provide a dust collector which shall be so constructed as to effectively prevent the escape of dust therefrom, but from which the accumulations of dust may be quickly and readily removed.

With the above and other objects in view, my invention consists in the construction and arrangement hereinafter described, and illustrated in the accompanying drawings, in which,

Figure 1 is a central longitudinal section of my improved dust collector, complete. Fig. 2 is a plan view of the same, the top plate being removed for the sake of clearness. Fig. 3 is an inverted plan view of the top plate. Fig. 4 is a plan view of one of the parts hereinafter described, and Fig. 5 is a plan view of the end ring.

Referring to the drawings in detail, my improved dust collector comprises a casing 1, preferably cylindrical, the walls of which are foraminous, and which may consist either of wire gauze or, as shown, of perforated sheet material. The upper end of the casing 1 is closed by means of an end plate 2, provided with a handle 3, by which the dust collector may be readily moved about. The end plate 2 is also provided with a number of perforated lugs 4, around its edge.

Into the lower end of the casing is fitted a ring 5 internally screw-threaded, and provided with a plurality of lugs 6, corresponding with the lugs 4 on the upper end plate. Rods 7 pass through pairs of corresponding lugs and are screw-threaded at one end to receive thumb-nuts 8, by means of which the two ends of the casing are secured together.

The end plate 2 is formed with a series of internally-projecting, annular, concentric ribs 9, the purpose of which will be hereinafter described. Resting on the ring 5 at the

lower end of the casing is a frame comprising a lower ring 10, an upper ring 11 of small diameter, and a plurality of radial arms 12, connecting the two rings, and of such length that the rings are held spaced apart, and the whole frame conforms to the shape of the frustum of a cone. The arms 12 are provided on their upper surface with a series of notches or steps 13, the purpose of which will now be described. Resting in these notches are a plurality of concentrically-arranged frames shown in the present instance as consisting of cylindrical partitions 14, preferably formed of wire gauze. Owing to the inclined position of the arms 12, it will be seen that these partitions 14 are disposed one within the other in stepped relation, the inner partition being the shortest, but the tops of all of the partitions lying substantially in the same plane, and some distance below the end plate 2.

Alternating with the frames or partitions 14 is a second set or series of similar partitions 15, which abut against the top plate 2 of the casing and are held in position by means of the ribs 9 thereon.

Secured to one end of the casing, as at 17, is one end of a continuous, tubular, web or fabric 16, which fabric is preferably of closely woven though porous material, and is looped back and forth around the ends of the above-described alternating frames or partitions. As will be seen from Fig. 1, this web or fabric passes over the tops of the frames or partitions 14 and under the bottom edges of the partitions 15, thereby forming a support for the same. The inner end of the fabric is brought together and closed, as at 18, and constitutes a top for the chambers formed by the innermost partition 14. It will therefore be seen that the two series of porous partitions, combined with the tubular web or fabric, form a series of annular, concentric chambers of tapering form, some of which as 23 open upward and the others, 24, downward. It will be observed, however, that the chambers 23 opening upward have no communication with the other chambers, and do not serve to collect the dust.

The lower end of the casing 1 is closed by means of a removable bottom 19, fitted with screw-threads 20, co-operating with the threads formed on the ring 5, just described. Projecting upwardly from the center of 110

this bottom 19, and preferably formed integral therewith, is a spout or conduit 21, which when the bottom is in position in the casing, projects well up into the innermost 5 chamber of the series. This spout or conduit is adapted to be connected with the discharge from any suitable fan or pump and thus serves to deliver dust-laden air into the casing. It will be seen, therefore, 10 that the dust-laden air entering the innermost chamber, filters through the porous partitions and associated fabric, the dust being retained by the partitions and fabric, and the air escaping through the outer walls 15 of the casing. It is to be noted that the dust is collected solely in the annular chambers which open downwardly, the other chambers being entirely closed. This will be obvious from the fact that, since the 20 dust laden air enters the casing on the lower side of the fabric, and since the fabric is continuous, the only way in which the air can escape, is by passing upwardly and radially through the fabric. The fabric thus acts 25 as a filter, and substantially all the dust is entrained thereby and deposited in the chambers which open downwardly. This construction results in the dust all accumulating on one side of the fabric and in one 30 end of the dust collector. It will, therefore, be apparent that, by simply removing the bottom 19, and gently tapping or jarring the casing, all of the entrapped dust will fall out of the lower end of the dust collector.

35 The end plate 2 is not secured rigidly to the casing 1, but can slide freely therein, and hence, by screwing up the thumb-nuts 8 and thus drawing in the end plate, the lower ends of the partitions 15 will be forced 40 against the loops of fabric in which they rest, and this serves to put and maintain the fabric under tension.

45 It will thus be seen that I have provided a dust collector which is simple to construct, and which may be very easily and readily cleaned, and it is thought the numerous advantages thereof will be readily appreciated by those skilled in the art.

What I claim is:

50 1. A dust collector comprising an outer foraminous casing, a plurality of frames nested one within the other within said casing, a filtering sack stretched over said frames and coöperating therewith to form a series of annular dust collecting chambers, all of which open toward the lower end of the casing, and a conduit for discharging dust-laden air centrally of the casing.

60 2. A dust collector comprising an outer foraminous casing, a plurality of frames nested one within the other in said casing, a filtering sack stretched over said frames and coöperating therewith to provide a series of concentric annular dust collecting chambers, 65 all of which open toward the lower end of the

casing, a removable closure for said end, and a conduit carried by said closure for discharging dust-laden air into the casing.

3. A dust collector comprising an outer foraminous casing having an imperforate 70 closure at the upper end and a removable closure at the lower end provided with an inlet opening for conducting dust-laden air into the casing, a plurality of frames nested one within the other within said casing, and a 75 filtering sack stretched over said frames and coöperating therewith to form a series of annular dust collecting chambers all of which open toward that end of the casing carrying the removable closure. 80

4. A dust collector comprising an outer foraminous casing having an imperforate closure at one end and a removable closure at the lower end provided with an inwardly projecting inlet spout for discharging dust-laden 85 air into the casing centrally thereof, a plurality of frames nested one within the other in said casing, and a filtering sack stretched over said frames to provide a series of annular dust collecting chambers all of which open 90 toward that end of the casing carrying the removable closure.

5. A dust collector comprising a foraminous cylindrical casing, top and bottom closures therefor, said bottom closure being removably attached to the casing and provided with an inlet for dust-laden air, a plurality of concentric partitions abutting directly against the top closure, a plurality of concentric partitions alternating with the 100 first and terminating short of the upper closure, means within the lower end of the casing for supporting the said last named partitions, and a tubular filtering sack secured at one end to said casing and looped back and 105 forth over said partitions to form a series of annular dust collecting chambers all of which open toward that end of the casing carrying the removable closure.

6. A dust collector comprising a foraminous cylindrical casing, a plurality of concentric partitions abutting against one end thereof, a plurality of concentric partitions of different lengths supported in stepped relation at the other end of the casing and alternating with the first named partitions, all of said partitions being of less length than the casing and the innermost one being the shortest, a continuous tubular web of filtering material looped back and forth over said partitions, thereby forming a series of annular concentric dust collecting chambers all of which open toward the lower end of the casing and a removable closure for said end. 110

7. A dust collector comprising an outer foraminous casing, concentrically arranged frames nested one within the other in said casing, a filtering sack stretched over said frames and coöperating therewith to provide a series of concentric annular dust collecting 125 130

chambers, all of which open toward the lower end of the casing, and a removable closure for said end, the arrangement being such that when the closure is removed, dust accumulations in the concentric chambers 5 may be dislodged therefrom and discharged through the said end of the casing.

8. A dust collector comprising an outer foraminous casing, a plurality of frames 10 nested one within the other within said casing, a filtering sack stretched over the ends of alternate frames and coöperating therewith to form a central dust receiving compart-

ment and a series of annular dust receiving chambers surrounding said central compartment and all of which open toward the lower end of the casing, and a conduit for discharging dust-laden air centrally of the casing and directly into said central compartment. 15

In testimony whereof I have affixed my 20 signature in presence of two witnesses.
